US00D325574S

United States Patent [19]

Carver

[11] Patent Number: Des. 325,574

[45] Date of Patent: ** Apr. 21, 1992

[54] **HAND HELD DATA COLLECTION TERMINAL WITH INTEGRAL DIODE LASER SCANNER**

[75] Inventor: Darryl L. Carver, Seattle, Wash.

[73] Assignee: Intermec Corporation, Everett, Wash.

[**] Term: 14 Years

[21] Appl. No.: 430,471

[22] Filed: Oct. 31, 1989

[52] U.S. Cl. D14/116; D14/100

CLAIM

The ornamental design for a hand held data collection terminal with integral diode laser scanner, as shown and described.

DESCRIPTION

FIG. 1 is a bottom right side perspective view of a hand held data collection terminal with integral diode laser scanner showing my new design;

FIG. 2 is a left side elevational view thereof;

FIG. 3 is a top plan view thereof; and,

FIG. 4 is a rear elevational view thereof.
